UNITED STATES PATENT OFFICE.

RAY C. NEWHOUSE, OF CHICAGO, ILLINOIS, ASSIGNOR TO ALLIS-CHALMERS MANUFACTURING COMPANY, OF MILWAUKEE, WISCONSIN, A CORPORATION OF DELAWARE.

COMMUNTING MILL.

Application filed April 15, 1926. Serial No. 102,120.

This invention relates in general to improvements in the art of reducing relatively hard substances to pulverulent condition by impact and abrasion, and relates 5 more specifically to improvements in the construction and operation of rotary drum mills for comminuting materials with the aid of a plurality of tumbling bodies cascading within the rotating drum.

10 An object of the invention is to provide an improved comminuting mill which is simple in construction and efficient in operation and which affords an exceptionally wide range of reduction.

15 It has heretofore been proposed to provide a so-called combination drum mill divided into a succession of coarse and fine grinding chambers by means of one or more partitions. It is a well known fact that 20 more efficient reduction of relatively coarse material is obtainable in a preliminary grinding chamber operated at a relatively high rate of speed and cooperating with a fine grinding chamber of greater length operated at a considerably lower rate of speed. While mills 25 have heretofore been constructed in which the diameter of the preliminary grinding chamber was considerably greater than that of the fine reduction chamber, the variation 30 in diameter of the two chambers of these prior mills was abrupt. It has been found that a relatively gradual change in diameter, and hence in the speed of operation, of the coarse and fine grinding chambers at the 35 place of mergence of the one with the other, produces more efficient reduction of the material. It is an object of the present invention to provide a combination mill having coarse and fine grinding chambers joined 40 by a gradually tapered connecting portion so that the material undergoes a gradual and uniform reduction while passing from chamber to chamber.

The present invention also contemplates 45 an improved system of comminuting material and of insuring delivery from the system of sufficiently comminuted materials only. In accordance with the improved system all material delivered from the mill, 50 which is insufficiently ground, is automatically returned for further reduction.

These and other objects and advantages will appear in the course of the following description.

A clear conception of an embodiment of 55 the invention and of the operation of devices constructed in accordance therewith, may be had by referring to the drawings accompanying and forming a part of this specification in which like reference characters 60 designate the same or similar parts in the various views.

Fig. 1 is a somewhat diagrammatic central vertical section through a rotary combination comminuting mill and means for separating the material which has been sufficiently reduced, from the oversize, and for returning the oversize to the mill for further reduction.

Fig. 2 is an enlarged central transverse 70 section through the medial portion of the improved comminuting mill.

Fig. 3 is an enlarged fragmentary central longitudinal section through the medial portion of the improved combination comminut- 75 ing mill.

The combination comminuting mill comprises in general a rotary drum which is divided into coarse and fine grinding chambers 80 3, 4 respectively by means of a transverse division head or partition; feed and discharge trunnions 23, 24 rotatably supporting the drum at its ends; and a gear 9 or other suitable means for continuously rotating the drum about its longitudinal axis. 85 The coarse grinding chamber 3 is located directly adjacent to the feed trunnion 23 and receives its supply of raw material from a feed mechanism 5, through the trunnion 23. The preliminary grinding chamber 3 is in- 90 closed by a cylindrical shell portion 17 of relatively large diameter, by an end head attached to one end of the shell portion 17, by a tapered shell portion 18 attached to the opposite end of the cylindrical portion 17, 95 and by the division head which is provided with discharge screens 26 located at the smaller end of the tapered portion 18. A

charge of relatively large freely tumbling comminuting bodies or balls 20 is located within the coarse grinding chamber 3, the perforations of the screen 26 being too small to permit passage therethrough of the balls 20, while permitting free delivery of comminuted material. The division head or partition comprises a transverse wall cooperat- 100 ing with the screen 26 to form a discharge space 27 which communicates with an an-

nular screening chamber surrounding the feed mechanism 5. In the chamber 3, the material is subjected to impact and abrasion by the cascading relatively heavy balls 20 cooperating with each other and with the liners 31, and the preliminarily reduced material is eventually discharged from the chamber 3 through the screen 26 to the annular screen 7. The screen 7 during its revolution with the drum, delivers the relatively fine material to the receptacle 19 and the oversize product is automatically returned to the chamber 3 for further reduction, by the return passages 25. As the mill continues to rotate, the scoops 8 intermittently pick up charges of the material in the receptacle 19 and deliver the same into the end of the fine grinding or finishing chamber 4 closely adjacent to the division head. In the chamber 4, the relatively fine material is further reduced to a fine powder by the abrasive action of the relatively small freely tumbling comminuting bodies 21. The fan 33 draws air through the finishing chamber 4 and this blast of air picks up particles of fine material and carries them through the hold back screen 22 and through the trunnion 24 into the chamber 6 wherein the relatively heavier particles gravitate into the buckets of the elevator 11 while the air with the lighter particles in suspension passes through the conduit 10 to the dust collector 12. The material which is picked up by the elevator 11 is eventually delivered to the separator 15 which separates the fine product from the oversize, the former being discharged to the final conveyer 13 and the latter being returned to the receptacle 19 for further reduction in the chamber 4. The dust collector 12 separates the fine product from the air blast, and likewise deposits the separated material in the conveyer 13. It will thus be noted that the comminuting system effectively reduces the material to a desired fineness and that oversize material is effectively separated and returned to the mill for further reduction.

The discharge trunnion 24 communicates with a discharge chamber 6 from which relatively fine material and air are withdrawn through a suction conduit 10 leading to a bag type dust collector 12, while coarser particles are removed by means of a bucket elevator 11. The elevator 11 is formed to deliver the relatively coarse particles to a centrifugal separator 15 through a spout 14, and the separator 15 is adapted to separate the sufficiently comminuted material from the oversize in a well known manner. The oversize material discharged by the separator 15 is conveyed to the receptacle 19 for further reduction by means of a conduit 16, while the final product is delivered from the separator 15 directly to a final discharge conveyer 13. The bag type dust collector 12 likewise discharges the material separated from the air passing therethrough, directly to the conveyer 13, and a single fan 33 or other suction device serves to draw dust laden air from the mill through the conduit 10 and dust collector 12, and to deliver the purified air from the comminuting system.

During normal operation of the installation, the raw material is fed through the trunnion 23 into the coarse grinding chamber 3 of the rotating drum, by means of the

It should be understood that it is not de- 130

sired to limit the invention to the exact details of construction and operation herein shown and described, for various modifications within the scope of the claims may 5 occur to persons skilled in the art.

It is claimed and desired to secure by Letters Patent:

1. In a comminuting mill, a cylindrical shell portion forming a preliminary reduction chamber, a cylindrical shell portion of smaller diameter forming a final reduction chamber, a tapered shell portion connecting said cylindrical shell portions, and freely tumbling comminuting bodies located within each of said shell portions. 65
2. In a comminuting mill, a cylindrical shell portion forming a preliminary reduction chamber, a cylindrical shell portion of smaller diameter forming a final reduction chamber, a tapered shell portion connecting said cylindrical shell portions, all of said shell portions being disposed concentric with respect to and rotatable about a common axis, and freely tumbling comminuting bodies located within each of said shell portions, the comminuting bodies in the preliminary reduction chamber having characteristics differing from those in the final reduction chamber. 70
3. In a comminuting mill, a cylindrical shell portion forming a preliminary reduction chamber, a cylindrical shell portion of smaller diameter forming a final reduction chamber, a tapered shell portion connecting said cylindrical shell portions, all of said shell portions being disposed concentric with respect to and rotatable about a common axis, and freely tumbling comminuting bodies located within each of said shell portions, the comminuting bodies in the preliminary reduction chamber being larger and heavier than those in the final reduction chamber. 75
4. In a comminuting mill, a single shell forming a comminuting chamber comprising cylindrical end portions of different diameters and a tapered intermediate connecting portion in open communication with said cylindrical chamber portion of largest diameter, means for introducing material into the end of said cylindrical chamber portion having largest diameter, means for discharging material from said tapered chamber portion at its smaller end, means for introducing material to one end of said cylindrical chamber portion having smallest diameter, means for discharging comminuted material from said cylindrical chamber portion having smallest diameter, and freely tumbling comminuting bodies located within each of said chamber portions. 80
5. In a comminuting mill, a cylindrical shell portion forming a preliminary reduction chamber, a cylindrical shell portion of smaller diameter forming a final reduction chamber, a tapered shell portion connecting said cylindrical shell portions, a partition spanning the interior of said mill to segregate said preliminary and final reduction chambers, and freely tumbling comminuting bodies located within each of said chambers. 85
6. In a comminuting mill, a shell comprising two cylindrical end portions of different diameters and an intermediate tapered connecting portion, a partition within said shell adjacent to said tapered portion, freely tumbling comminuting bodies located within each of said shell portions, means for introducing material into said shell portion of largest diameter, means for discharging comminuted material from said shell portion of smallest diameter, and means for discharging material from said shell on one side of said partition and for returning some of said material to said shell on the opposite side of said partition. 90
7. In a comminuting mill, a shell forming segregated comminuting chambers, means for feeding material into one of said chambers, means for delivering comminuted material from the other of said chambers, a pneumatic separator for treating the material delivered from said other chamber, and means for introducing rejects from said separator into said other chamber. 95
8. In a comminuting mill, a shell forming segregated comminuting chambers of different diameters, means for introducing material into said chamber having largest diameter, means for delivering material from said chamber having largest diameter and for introducing a part of said material into said chamber of smallest diameter, means for delivering material from said chamber of smallest diameter, a separator for treating the material delivered from said chamber of smallest diameter, and means for returning the rejects from said separator to said chamber of smallest diameter with the material introduced thereto from said chamber of largest diameter. 100
9. In a comminuting mill, a shell forming a comminuting chamber comprising two cylindrical portions of different diameters and a tapered connecting portion, a plurality of relatively large freely tumbling comminuting bodies disposed within said portion of largest diameter, and a plurality of relatively small freely tumbling comminuting bodies disposed within said portion of smallest diameter. 115
